Regent Lighting spec. sheet showing Model SL500 and Model TSL1000; admitted prior art (prior to Dec.-1994).

Primary Examiner—Susan J. Lucas[57] **CLAIM**

The ornamental design for a utility light for use with a clamp, as shown and described.

DESCRIPTION

FIG. 1 is a front perspective view of a utility light for use with a clamp;

FIG. 2 is a side view thereof;

FIG. 3 is a front view thereof;

FIG. 4 is a rear view thereof.

The broken lines are shown for illustrative purposes only and form no part of the claimed design.
